(57) **CLAIM**

The ornamental design for a fire pit barrier as shown and described.

DESCRIPTION

This application is related to U.S. patent application Ser. No. 18/759,191, filed Jun. 28, 2024, entitled Fire Pit Barrier, the entire disclosure of which is hereby incorporated herein by reference.

FIG. 1 is a top front perspective view of a fire pit barrier showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a view similar to FIG. 1 but with additional broken lines; and,

FIG. 9 is a view similar to FIG. 2 but with additional broken lines.

The broken lines in FIGS. 1-9 illustrate unclaimed portions of the fire pit barrier and form no part of the claimed design. The additional broken lines in each of FIGS. 8-9 illustrate unclaimed environmental structure that forms no part of the claimed design, which unclaimed environmental structure includes a fire pit for the fire pit barrier.

The surface shadings and contour lines shown in FIGS. 1-9 represent the three-dimensional character and contour of the fire pit barrier.
